UNITED STATES PATENT OFFICE.

FRANK SUCHOVSKY, OF HOBOKEN, NEW JERSEY.

LIFE-BOAT PROTECTOR.

1,243,117.

Specification of Letters Patent.

Patented Oct. 16, 1917.

Application filed May 16, 1917. Serial No. 169,002.

To all whom it may concern:

Be it known that I, FRANK SUCHOVSKY, a subject of the King of Hungary, residing at Hoboken, in the county of Hudson and 5 State of New Jersey, have invented certain new and useful Improvements in Life-Boat Protectors, of which the following is a specification.

This invention relates to certain new and 10 useful improvements in life boat protectors.

The primary object of the invention is 15 the provision of a protector for boats such as life boats which are either propelled manually or by a motor, the arrangement being such as to present a bullet shield forwardly of the boat and a torpedo proof enclosure substantially surrounding the boat.

A further object of the device is the arrangement of an adjustably mounted forwardly positioned buffer upon a boat serving as a protection against missiles and offers but a slight resistance to the travel of the boat, and ready means for adjusting a device being arranged upon the boat.

25 In the drawing forming a part of this application and in which like designating characters refer to corresponding parts throughout the several views:

Figure 1 is a side elevation of a boat provided with the present device.

30 Fig. 2 is an enlarged vertical central sectional view through a portion thereof, parts being illustrated in side elevation.

Fig. 3 is a top plan view of the same.

35 Fig. 4 is an enlarged sectional view taken upon line IV-IV of Fig. 3, and

Fig. 5 is a detail sectional view taken upon line V-V of Fig. 4.

The boat protector herein illustrated is 40 serviceable in the time of war in the protection of smaller boats and ships whereby the projectiles and torpedoes of the enemy will be prevented from hitting and damaging the same. A motor boat 10 is herein 45 illustrated provided with the present device which broadly consists of a metal inclosing screen or cage 11 overlying and substantially surrounding the entire boat excepting the bottom portion thereof.

50 The cage 11 comprises a top 12 arranged in parallelism above the deck 13 of the boat 10 and may be supported upon the roof of the pilot house 14 if desired while opposite depending sides 15 are carried by the top of 55 the cage terminating forwardly in a bow-

post 16 and rearwardly in a stern post 18, brackets 19 being connected between the said posts and the bow and stern respectively of the boat 10. The bottom of the cage is open and this together with the fact 60 that the cage is formed of grating offers little resistance to the operation of the boat. The top of the cage prevents the boat from being endangered by bombs from aeroplanes while the sides 15 protect the boat from tor- 65 pedoes and large projectiles. A buffer form of bullet shield 20 is mounted forwardly of the boat by means of a rearwardly projecting rack 21 carried by the top 22 of the shield, the said rack being slidably ar- 70 ranged upon the central beam 23 of the cage top 12 being retained thereon by means of overlying straps 24.

The teeth 25 of the rack 21 are arranged within a central longitudinal slot 26 of the 75 said beam 23 and are extended upon the lower face of the buffer top 22 while a gear 27 in constant mesh with the said teeth is journaled in brackets 28 depending from the beam 23.

A windlass 29 is arranged upon the boat deck 13 operatively connected by means of a sprocket chain 30 on a sprocket wheel 31 upon the shaft 32 of the gear 27. It will be understood that by operating the windlass 85 29 the gear 27 may be turned in the desired direction for longitudinally shifting the rack 21 and the buffer 20 as found desirable either toward or away from the bow of the boat 10.

A spring pressed locking bolt 33 is provided in a housing 34 carried by one of the brackets 28 for engaging within the sockets 35 arranged around the shaft 32, a pull cord 36 being carried by the said bolt 33 for releasing the same when it is desired to turn the shaft 32 for shifting the buffer 20.

Perforations 37 are provided through the buffer 20, the latter being V-shaped in cross-section and whereby the same offers but 100 slight resistance to the forward progress of the boat 10 but affords a bullet proof wall in advance of the boat for the protection thereof.

The use and value of the cage 11 will be 105 apparent from the foregoing description as well as that of the buffer shield 20, it being noted that the shield 20 may be retracted rearwardly to a position substantially inclosing the forward portion of the 110

cage 11 thereby rendering the same more fully armored while the buffer shield may be projected until the up-turned flange 38 at the rear end of the rack 21 engages the 5 rearmost strap 24 and at which time the buffer is arranged considerably in advance of the bow post 16 of the cage 11.

A protector is arranged which renders traveling upon the high seas less dangerous 10 during war times while the same is so arranged as not to overweight the boat nor to materially affect the speed thereof. It will be understood that the grating of which the cage 11 is composed may be of any desired mesh while removable portions 39 may 15 be provided at convenient points.

Copies of this patent may be obtained for five cents each, by addressing the "Commissioner of Patents, Washington, D. C."

What I claim as new is:—

In combination with a boat, a protector therefor comprising an inclosing cage having a central top beam provided with a longitudinal slot, a bullet shield arranged forwardly of the cage adapted for overlying the bow portion thereof when retracted, a rearwardly projecting rack carried by the said shield having the teeth thereof arranged 20 within said slot, a gear in constant mesh with said teeth operable from the deck of the boat and locking means for the said gear.

In testimony whereof I affix my signature. 30

FRANK SUCHOVSKY.
